UNITED STATES PATENT OFFICE.

ARCHIBALD D. McKELLAR, OF CHICAGO, ILLINOIS.

SIGN.

1,245,365.

Specification of Letters Patent.

Patented Nov. 6, 1917.

Application filed February 23, 1917. Serial No. 150,491.

To all whom it may concern:

Be it known that I, ARCHIBALD D. McELLAR, a citizen of the United States, and a resident of the city of Chicago, county of 5 Cook, and State of Illinois, have invented certain new and useful Improvements in Signs, of which the following is a specification.

My invention relates to improvements in 10 signs, and has for its object the provision of an improved moving sign which is of simple construction and efficient in operation, which permits of the exhibition of a large number of signs, and in which the 15 character of the signs may be readily changed or varied.

The invention consists in the combinations and arrangements of parts hereinafter described and claimed.

20 The invention will be best understood by reference to the accompanying drawings forming a part of this specification, and in which,

Figure 1 is a face view of a sign, embodying my invention,

Fig. 2, a vertical transverse section of the same,

Fig. 3, another vertical transverse section of the same;

30 Fig. 4, a detail view of one of a plurality of letter sign plates employed in the construction,

Fig. 5, a longitudinal vertical section taken substantially on line 5—5 of Fig. 2,

35 Fig. 6, a detail view illustrating a portion of feeding mechanism employed in the construction,

Fig. 7, a side view of one of the letter sign plates,

40 Fig. 8, a horizontal section of the construction,

Fig. 9, a vertical longitudinal section taken through the upper portion of the construction, and

45 Fig. 10, a detail view illustrating the means employed for discharging the sign members, shown in position of use.

The preferred form of construction as 50 illustrated in the drawings comprises a sheet metal casing 11 having a plurality of glass covered side openings 12 in the face thereof. Horizontal shafts 13 and 14 are arranged in the casing 11, one above the other, as indicated, the shaft 13 being mounted in vertically adjustable bearing slides 13'. A 55 plurality of pairs of vertically alining

sprocket wheels 15 are fixed to the shafts 13 and 14, and coöperating pairs of feed chains 16 are passed over said sprockets, said feed chains carrying transversely alining lugs 17, as indicated. Guide plates 18 are positioned at the sides and between the pairs of feed chains 16, said guide plates being provided with serrated or zigzag rear edges 19, as shown. Corresponding hopper plates 20 are arranged in the rear of casing 11 with their forward edges serrated or zigzag in form to coöperate with the rear edges of plates 18 to form, in effect, zigzag guide slots adapted to receive the laterally projecting ends of guide rods 22, secured at the upper edges of letter sign plates 23, as indicated. Guide bars 24 having serrated or zigzag forward edges 25 are positioned at the rear of casing 11 to coöperate with the 75 corresponding zigzag slots between plates 18 and 20 to constitute guides for the rear edges of plates 23 as they travel downwardly through the corresponding hoppers in the casing 11, said serrated edges 25 and said 80 zigzag guide slots thus serving to partially support the upper plates of a stack or pile of plates and thus relieving the lowermost plates from undue pressure.

A supporting table 26 is arranged under 85 the rear portion of each of the hoppers between the plates 20, and corresponding feed chains 27 carrying engaging lugs 28 are mounted upon pairs of sprockets 29 on shafts 30, as shown, said feed chains and lugs being 90 positioned to cause said lugs to engage the laterally projecting ends of rods 22 and withdraw the lowermost sign plates 23 from the corresponding hoppers. Shaft 30 carries a sprocket 31 driven by a sprocket chain 95 32 from a sprocket 33 on shaft 14, which, in turn, is driven by an electric motor 34, as best shown in Fig. 3. A supplemental supporting table 35 is also arranged under each of the tables 26 to guide the rear edges of 100 the plates 23 as they travel under the domination of chains 27. The parts are so arranged that the plates 23 will be automatically withdrawn from certain hoppers and fed into operative relation with the lugs 105 17 on the chains 16 to be engaged thereby as indicated in Fig. 2. Guide plates 36, 37 and 38 are arranged about the corresponding plates 18 to form guide slots for the rods 22. The upper forward edges of plates 39 are 110 beveled as shown to permit of the free movement of the plates 23 about the upper

sprockets 15, and plates 38 form guide slots 40 for guiding the rods 22 during the same movements. The rear portions of the guide slots 40 communicate with the upper portions 5 of the zigzag slots above mentioned, so that as each sign plate travels around the corresponding upper sprockets 15, it is tilted as indicated in Fig. 2 and discharged from the corresponding feed chains 16, the rods 22 traveling through the rear portions of slots 10 40 into said zigzag slots. Here the sign plates are turned over by the action of the zigzag slots and their rear edges caused to rest upon the serrations 25, as they travel 15 downwardly in the corresponding hoppers. By this arrangement it will be observed that a large number of plates 23 may be arranged and stacked in the respective hoppers to form a large number of different signs, and 20 said plates will be automatically withdrawn from said hoppers, arranged to form the various signs and then automatically discharged into the hoppers again.

In order to effect discharge of the sign 25 plates 23 from the casing 11 for changing of the signs, guide fingers 41 are arranged as indicated on a shaft 41' having an operating handle 42 provided with a lock pin 43 adapted to engage one of a plurality of lock 30 holders 44 formed in the casing 11, as indicated. The guide fingers 41 are arranged to constitute the upper rear portions of the slots 40 when positioned as shown in Figs. 2 and 3 or to be elevated, as indicated by 35 dotted lines in Fig. 2, or depressed into the position shown in Fig. 10 to effect discharge of the plates. To facilitate entry or discharge of the plates 23, guide plates 45 are positioned to coöperate with plates 38 and 40 20 to form slots 46 and 47, slots 46 constituting rearward tangential prolongation of slots 40 and slots 47 constituting entry slots for the rod ends 22. Deflecting leaves or plates 48 are secured to a shaft 49 in positions 45 to be swung downwardly to rest upon lugs 48' to constitute deflectors to further assist the discharge of the plates 23. Shaft 49 is equipped with an operating handle 50 carrying a lock pin 51 to facilitate manipulations thereof, and discharge slots 52 are provided to permit the discharge of the plates 23. By this arrangement when it is desired to discharge the sign plates, the fingers 41 are depressed and the deflector 50 plates 48 are swung downwardly whereupon the sign plates will be automatically discharged by the automatic action of the mechanism. The newly arranged sign plates are inserted from the top, the ends of 60 the rods 22 traveling in the slots 47, for which purpose both the fingers 41 and the deflector plates 48 are elevated. Suitable electric light bulbs 53 are arranged in the casing 11, as indicated, for illuminating purposes.

While I have illustrated and described the preferred form of construction for carrying my invention into effect, this is capable of variation and modification without departing from the spirit of the invention. I, 70 therefore, do not wish to be limited to the precise details of construction set forth, but desire to avail myself of such variations and modifications as come within the scope of the appended claims. 75

Having described my invention what I claim as new and desire to secure by Letters Patent is:

1. A sign comprising a conveyer; sign members on said conveyer; and manually 80 controlled means for automatically discharging said sign members, substantially as described.

2. A sign comprising a plurality of adjacent conveyers; letter sign members on each 85 of said conveyers coöperating with those on the others to complete a sign; means for automatically removing said sign members from said conveyers and stacking them in piles; and means for automatically removing the bottommost sign members from said piles and remounting them on said conveyers, substantially as described. 90

3. A sign comprising a plurality of adjacent conveyers; sign members on each of 95 said conveyers coöperating with those on the others to complete a sign; and manually controlled means for automatically discharging said sign members, substantially as described. 100

4. A sign comprising a plurality of adjacent conveyers; sign members on each of said conveyers coöperating with those on the others to complete a sign; means on said conveyers for automatically discharging and 105 reëngaging said sign members; and manually controlled means for automatically discharging said sign members, substantially as described.

5. A sign comprising a plurality of adjacent conveyers; sign members on each of said conveyers coöperating with those on the others to complete a sign; means for automatically removing said sign members from said conveyers and stacking them in 110 piles; means for automatically removing the bottommost sign members from said piles and remounting them on said conveyers; and manually controlled means for automatically discharging said sign members, substantially as described. 115

6. A sign comprising a casing; two parallel shafts in said casing one above the other; a plurality of pairs of sprocket wheels on said shafts; sprocket chains traveling over said sprocket wheels; transversely alining lugs on said sprocket chains; hoppers in said casing corresponding with said pairs of sprocket chains; sign letter plates arranged in piles in said hoppers; laterally projecting 120

125

130

- pins on said plates, there being guide slots for said pins arranged to guide said plates, the slots arranged to guide said plates during their travel through said hoppers being zigzag in form; a zigzag guide for the edges of said plates opposite said pins; traveling chain conveyers located under each of said hoppers; and lugs on said last mentioned conveyers arranged to engage the pins on the bottommost sign members in said hoppers and carry said bottommost sign members in operative relation with the lugs on said first mentioned sprocket chains, substantially as described.
- 15 7. A sign comprising a casing; two parallel shafts in said casing one above the other; a plurality of pairs of sprocket wheels on said shafts; sprocket chains traveling over said sprocket wheels; transversely alining lugs on said sprocket chains; hoppers in said casing corresponding with said pairs of sprocket chains; sign letter plates arranged in piles in said hoppers; laterally projecting pins on said plates, there being
- 20 guide slots for said pins arranged to guide said plates, the slots arranged to guide said plates during their travel through said hoppers being zigzag in form; a zigzag guide for the edges of said plates opposite said pins; traveling chain conveyers located under each of said hoppers; lugs on said last mentioned conveyers arranged to engage the pins on the bottommost sign members in said hoppers and carry said bottommost sign members in operative relation with the lugs on said first mentioned sprocket chains; and a manually controlled deflector arranged to engage and discharge said sign members from said casing, substantially as described.
